United States Patent Office.

WILLIAM D. FIELD, OF PROVIDENCE, RHODE ISLAND.

Letters Patent No. 77,267, dated April 28, 1868.

IMPROVEMENT IN DOOR-LOCKS.

The Schedule referred to in these Letters Patent and making part of the same.

TO ALL WHOM IT MAY CONCERN:

Be it known that I, WILLIAM D. FIELD, of the city and county of Providence, and State of Rhode Island, have invented a new and improved Changeable-Combination Lock; and I do hereby declare that the following is a full, clear, and exact description thereof, which will enable those skilled in the art to make and use the same, reference being had to the accompanying drawings, forming part of this specification, in which—

Figure 1 represents a front elevation, partly in section, of my improved lock.

Figure 2 is a similar view, showing the parts in different positions.

Figure 3 is a vertical transverse section of the same, the plane of section being indicated by the line xx , fig. 2.

Figure 4 is a detail transverse section of the same, taken on the line yy , fig. 2.

Figure 5 is a side view, partly in section, of my improved key.

Figure 6 is a transverse section of the same, the plane of section being indicated by the line zz , fig. 5.

Similar letters of reference indicate corresponding parts.

This invention relates to a new changeable-combination lock, which is so arranged that it can be applied to doors, and that it can be changed without inconvenience, by simply removing the inner plate.

The invention consists, first, in hinging a set of tumblers, by means of knuckle-joints, to the inner end of the bolt, in such a manner that they will be moved back and forth by the motion of the bolt, and so that they can be easily taken off and changed, whenever desired.

The invention consists, second, in grooving the edges of the bolt, and in providing arms projecting from the outer plate of the lock-case into these grooves, so that the bolt, and with it its appendages, may be held on the lock-case when the inner plate of the same is removed for the purpose of changing the tumblers.

The invention consists, third, in arranging an adjustable guard above the tumblers on the outer case-plate, in such a manner that the ends of the tumblers will strike against the guard when the tumblers are raised too high by a false key, so that the tumblers cannot be moved back and the bolt not drawn back by any other but the correct key.

The invention consists, fourth, in providing both ends of the key with adjustable wards, those on one end being arranged in a reverse order to those on the other end, so that one end of the key may be used for opening or locking from the inside, while the other end will operate from the outside.

The wards of the key do only raise the tumblers, and do not operate the bolt.

And the invention consists, fifth, in arranging a slotted revolving sleeve between the key-holes into which the end of the key is fitted, the wards fitting through the slot in the sleeve, so that they carry the sleeve around with them when the key is turned.

The sleeve carries a projecting arm, which strikes against arms projecting from the bolt, so as to move the bolt after the wards have raised the tumblers.

The invention finally consists in forming the arms, which project from the bolt, on a plate, which is secured upon the inner face of the bolt, so as to cover the junction of the tumblers and bolt.

The tumblers are thereby held in place, and by unscrewing the inner lock-case plate, and then the aforesaid plate forming the bolt-arms, the tumblers are laid bare, and can be changed at will, the wards of the key being changed accordingly.

A represents the case or shell of the lock.

The same consists of the outer plate, a , and the inner plate, b , to one of which the sides of the case are secured.

B represents the bolt.

The same passes through a side-plate of the case, and if the side-plates are formed on the inner plate, b , as shown, the bolt would fall out if the inner plate is taken off the case.

To avoid this the upper and lower edges of the bolt are grooved or tongued, and bent plates C C are secured

to the outer plate *a*, fitting into the grooves of the bolt, as shown in fig. 4, or receiving the tongues of the bolt in grooves provided in their faces.

The outer plate *a* is, by means of screws *c c*, or otherwise, secured to the door, and the inner plate *b* is, by means of screws *d*, secured to the outer plate, so that, when the lock is to be changed, the inner plate only need be taken off, without requiring the removal of the whole lock.

When the inner plate is thus taken off, the bolt will either be held in the side plate, projecting from the outer plate, or, if the side plates are formed on the inner plate, it will be held by means of the guide-plates *C C*, as aforesaid, so that it cannot fall out.

D D are the tumblers.

The same are hinged, by means of knuckle-joints *e*, to the inner end of the bolt, as is clearly shown in fig. 2, and are, by means of springs *f f*, pressed towards the key-hole against the edge of a fixed guard, *g*, which fits into notches formed on the tumblers, when the bolt is locked or unlocked.

E is a plate, screwed upon the inner face of the bolt, so as to cover the hinged ends of the tumblers, to prevent them from falling out, when the inner plate *b* is removed, and to lock them to the bolt.

The plate *E* has two arms, *h* and *i*, which project downwards, and which form the catches by means of which the bolt is drawn back and forth.

F is the key.

The same is provided with adjustable wards, *j j*, on each end, the same being marked, so that they can be set in accordance with the arrangement of the tumblers.

They are fitted into the slotted tubular ends of the key, and are held in position by means of a headed screw, *k*, as is clearly shown in figs. 5 and 6.

G is a tube, pivoted between the plates *a* and *b*, and between the key-holes, so as to receive the key-spindle.

It is slotted to receive the wards.

When the key is inserted, the tube *G* will be turned by means of the wards, and will, after the wards have raised the tumblers off the guard-plate *g*, strike, with an arm, *l*, with which it is provided, as shown, against one of the arms *h* or *i*, projecting from the bolt, and will thereby move the bolt in or out, as the case may be.

When the bolt is locked, the parts are all in the position indicated in fig. 1.

H is an adjustable plate, screwed upon the plate *a* above the tumblers, and carries an arm, *m*, which is beyond the inner ends of the tumblers, when the bolt is locked, its outer edge being about in line with the inner ends of the tumblers, as shown in fig. 1.

When the tumblers are raised by a false key, which has not the exact correct wards, some of them will either not be raised off the guard *g* if some of the wards of the false key are too short, or some of the tumblers will, by too long wards, be raised too high, as shown by red lines in fig. 1, so that, when an attempt is made to move the bolt back, the inner ends of the tumblers will strike against the guard *m*, thereby preventing the bolt from being unlocked, or, if the tumblers are not raised off the guard *g*, the bolt will also be prevented from being unlocked.

From the foregoing, the operation of the lock will be easily understood.

When the tumblers are to be changed, the outer plate *b* is taken off and also the plate *E*. The tumblers can then be easily taken off and changed. The wards of the key will then have to be changed accordingly, but in reversed order, on the opposite ends of the key, so that the lock may be operated from the outside by one end, and from the inside by the other end of the key.

I claim as new, and desire to secure by Letters Patent—

1. Providing the bolt *B* with tongued or grooved edges, substantially as set forth, and combining it with the guide-plates *C C*, as described, so that it will remain on the lock when the inner plate of the same is removed, substantially as herein shown and described.

2. Forming the arms *h* and *i*, by means of which the bolt is moved, on a plate, *E*, which is screwed upon the bolt, so that the tumblers are held in place by the said plate, and can be removed when the same is taken off, substantially as herein shown and described.

3. The bolt *B*, plate *E*, oscillating and sliding tumblers *D*, springs *f*, and revolving tube *G*, having a projecting arm, *l*, all arranged in combination with each other and with the key *F* having changeable wards, and all made and operating substantially as herein shown and described.

WILLIAM D. FIELD.
